CLAIM

The ornamental design for tabletop video camera, as shown and described.

DESCRIPTION

FIG. 1 is a top perspective view of a tabletop video camera showing our new design;

FIG. 2 is a front elevational view thereof;

FIG. 3 is a side elevational view thereof, the undisclosed opposite side being a mirror image thereof;

FIG. 4 is a rear elevational view thereof;

FIG. 5 is a top plan view thereof; and,

FIG. 6 is a bottom plan view thereof.

The flexible gooseneck is shown fragmented and broken away to indicate intermediate length.
